San Diego, Calif., a corporation of California

Application August 19, 1946, Serial No. 132,642

Term of patent 14 years

(Cl. D52—6)

To all whom it may concern:

Be it known that we, Henry I. Mandolf, a citizen of the United States and a resident of San Diego, in the county of San Diego and State of California, and John B. Morrow, a citizen of the United States and a resident of San Diego, in the county of San Diego and State of California, have invented a new, original, and ornamental Design for Combined Weighing and Measuring Device, of which the following is a specification, reference being had to the accompanying drawing, forming a part thereof.

In the drawing:

Figure 1 is a perspective view of a combined weighing and measuring device, showing our new design;

Figure 2 is a bottom view, and

Figure 3 is a side elevational view.

The rear of the device is substantially plain.

We claim:

The ornamental design for a combined weighing and measuring device, substantially as shown and described.

HENRY I. MANDOLF.
JOHN B. MORROW.
